(57) **CLAIM**

I claim the ornamental design for a portion of a windshield wiper, as shown and described.

DESCRIPTION

FIG. 1 is a perspective view of a portion of a windshield wiper embodying my invention.

FIG. 2 is a top plan view of the portion shown in FIG. 1.

FIG. 3 is an enlarged left end view of the portion as seen in FIG. 2.

FIG. 4 is an enlarged right end view of the portion as seen in FIG. 2.

FIG. 5 is a front elevational view of the portion of a windshield wiper shown in FIG. 1; and,

FIG. 6 is a rear elevational view of the portion of a windshield wiper shown in FIG. 1.

The present application is directed to the shape and contour of the design illustrated in the drawings. The broken line showing of the environment in FIGS. 1-6 is for illustrative purposes only and forms no part of the claimed design. The bottom of the portion shown in FIGS. 1-6 is not part of the claimed design.
